(57) **CLAIM**

The ornamental design for an insulated collapsible cup, as shown and described.

DESCRIPTION

FIG. 1 is a perspective view of the insulated collapsible cup in accordance with the present invention;
FIG. 2 is an alternate perspective view thereof;
FIG. 3 is a top plan view thereof;
FIG. 4 is a bottom plan view thereof;
FIG. 5 is a front elevational view thereof;
FIG. 6 is a rear elevation view thereof;
FIG. 7 is a left side elevation view thereof; and,
FIG. 8 is a right side elevation view thereof.
The broken lines in the drawings depict portions of the insulated collapsible cup that form no part of the claimed design.

1 Claim, 5 Drawing Sheets
